ABSTRACT: A gas-heated flatiron having a soleplate on which a cover shell is mounted which is separated into a main chamber and a rear chamber spaced apart by a heat-insulating cross partition, the main chamber supporting a housing for a heat-radiating infrared ray emitting flame plate connected to the rear chamber through a gaseous combustion mixture feeding pipe facing a nozzle housed in said rear chamber. The nozzle being connectable to a gas supply source and the rear chamber being open to atmosphere so that injection of gas and entrained air is injectable into said gaseous combustion mixture feeding pipe. Said nozzle is accessible from outside and thereby interchangeable without having to disassemble the flatiron.

GAS-HEATED FLATIRON

BACKGROUND OF THE INVENTION

Field of the Invention

The present invention relates to a gas-heated flatiron and is particularly useful in those areas of the country where portable gas containers are used.

SUMMARY OF THE INVENTION

The gas-heated flatiron according to the present invention comprises a soleplate defining a smoothing plane and having a front end portion and a rear end portion; a cover shell is mounted on said soleplate and projects beyond said rear end portion and is located above said smoothing plane. The flatiron is further provided with an operating handle mounted on said cover shell. The cover shell defines with said soleplate and said partition a main chamber and a rear chamber, the latter projecting beyond the rear end portion of said soleplate. The rear chamber is heat insulatedly separated from said main chamber by said heat-insulating cross partition. A bell-shaped housing is supported by said cover shell within said main chamber and has a heat-radiating infrared ray emitting flame plate mounted therein. The flame plate has a plurality of gaseous combustion mixture passages directed towards the soleplate and is spaced apart therefrom. A gaseous combustion mixture feeding pipe enters said housing above said flame plate. The feeding pipe sealingly passes through the heat-insulating cross partition and the housing. Furthermore, a nozzle is housed in said rear chamber and has its ejector axis directed into said gaseous combustion mixture feeding pipe. The nozzle is accessible from outside, so that it can be easily cleaned and/or replaced. A gas-feeding flexible conduit member is connected to the nozzle and supported by the operating handle. The gas-feeding conduit member is connectable to a gas supply source through valve means which control the flow of gas towards the nozzle.

It is an object of the present invention to provide a gas-heated flatiron of simple structure and easy handling, which may operate continuously without overheating the soleplate, because the flame plate arrangement is balanced as to its thermal output, at the same time as the distance existing between the flame plate and the soleplate is such, that the flame cannot back away.

A further object of the present invention is to provide a flatiron having a gas injector nozzle which is accessible from outside, so that in case of obstruction it may be easily cleaned without having to disassemble the structure.

BRIEF DESCRIPTION OF THE DRAWINGS

In order to explain the present invention with more specific details, reference will now be made to the accompanying drawings, wherein a preferred embodiment is shown by way of example, and wherein:

FIG. 1 is a perspective view of the flatiron of the present invention, including valve means for controlling the flow of gas and further shows part of a gas tank which does not form part of the present invention and which represents the gas supply source.

FIG. 2 is a longitudinal section through the flatiron.

FIG. 3 is a perspective view of the cover shell (which has been turned upside down) and the means contained therein, with the flame plate only partially shown and with the soleplate having been removed.

FIG. 4 is a detail, in perspective view, of the nozzle and the means mounting said nozzle in the rear chamber of the cover shell.

FIG. 5 is a perspective view of the nozzle member.

FIG. 6 is a perspective view of a tool for cleaning the nozzle.

FIG. 7 is a perspective view of the heat-radiating infrared ray emitting flame plate.

FIG. 8 is a side elevation seen from the inside of one-half of the operating handle, and

FIG. 9 is a longitudinal section of the valve means.

DESCRIPTION OF THE PREFERRED EMBODIMENT

As may be appreciated from FIG. 1, the flatiron 10 of the present invention, comprises a soleplate 11 defining a smoothing plane 12. The soleplate 11 has a front end portion 13 (see FIG. 2) and a rear end portion 14. Within the soleplate 11, a front stud 15 and a pair of rear studs—only one being visible in FIG. 2 and identified by reference numeral 16—are mounted defining an isosceles triangle. A cover shell 17 is mounted on said soleplate 11 and having countersunk hole portions 18 through which said studs 15, 16 pass. Nuts 19 are screwed on said studs 15, 16 and retain the cover shell 17 on said soleplate 11.

The inside of the cover shell 17 (see FIG. 3) is divided by a heat-insulating cross partition 20 into a main chamber 21 and a rear chamber 22. The sidewall portions of the cover shell 17 corresponding to the main chamber 21 define cutout portions 23, which give access to outside air into said main chamber 21.

The cover shell 17 is longer than said soleplate 11, so that the rear portion of the said cover shell 17 projects beyond and above the rear end portion 13 of the soleplate 11, and thus becomes located above said smoothing plane 12. More particularly, the heat-insulating cross partition 20 is still within the field of the soleplate 11, but the main portion of said rear chamber 22 is outside of the range of said soleplate 11. The backwardly sloped upper zone 22 of said cover shell 17, which contains said countersunk hole portions 18, furthermore defines four embossed portions 25 (only two being visible in FIG. 2), connected by means of spot welding to four complementary embossed portions 26 (only two being visible in FIG. 3), forming part of a spaced-apart platform 27 having a pair of upwardly projecting ears 28, 29. The platform 27 defines an outer-channelled portion 30, having spaced-apart spacer projections 31 and holes 32 (only one being visible in FIG. 2), giving access to nuts 19.

A two-part assembled operating handle 33, molded from a thermal insulating material, is mounted on said platform 27 and more particularly on said spacer projections 31, so that good air circulation is assured to cooperate in cooling the handle 33 with regard to the heat-emitting means to be described later on, and housed within the main chamber 21 as well as the heat emitted by the soleplate 11. The rear leg 34, formed by the operating handle halves 40, 41, provides a projecting member 35 which, as is well known in the art, enables placing the iron in an upraised inoperative position by placing it on said projecting member 35 and the rear face 36 cover shell 17. Each of the half handle portions 40, 41 of handle 33 has at its front end portion, a thumb-accommodating recess 37 (FIG. 1). One of the operating handle halves and more particularly, handle half 40, shown in FIG. 2, has a reinforced opening supporting a cord lift bushing 38, through which a gas-feeding flexible conduit member 39 passes.

As to the specific details of the operating handle 33, the latter consists of the pair of operating handle halves 40 (FIG. 2) and 41 (FIG. 8). The operating handle half 41 comprises a pair of front bushings 42, 43 and a pair of rear bushings 44, 45 arranged within the inside of said handle half 41. Handle half 41 is first mounted on the platform 27, so that the bushings 43, 45 face the elongated slots 46, 47 respectively, and can then be connected to said upwardly projecting ears 28, 29 by pertinent bolts 48, 49, respectively. Thereafter, the other operating handle half 40 is mounted onto the platform and connected to the handle half 41 by means of a pair of screws 50, 51 (FIG. 2) which are housed in said handle half 40 and screwed into said bushings 42, 44 of the other handle half 41 (FIG. 8), respectively.

Within the main chamber 21 a bell-shaped housing 52 (FIGS. 2 and 3) is spotwelded by its roof 53 to the backwardly sloped upper zone 24 of the cover shell 17. The spotwelded zones are identified by reference numeral 54. The bell-shaped housing 52 has its opening faced towards the soleplate 11,

which in the zone facing said opening, has transverse indentations 55 (FIG. 2) to increase the surface which will receive the heat of the flame. The free end of the bell-shaped housing 52 is provided with four bendable lugs 56, for retaining a substantially rectangular heat-radiating infrared ray emitting flame plate 57, surrounded by a heat-resistant sealing strip 58. The flame plate has the customary gaseous combustion mixture passages 59. Once the flame plate 57 together with the sealing strip 58 is housed in the housing 52, as shown in FIG. 3, the lugs 56 are bent over the flame plate 57, thereby retaining it flush with the edge defining the opening of said housing and forming a space in between said flame plate 57 and roof 53. Conveniently, as shown in FIG. 7, the flame plate 57 has two central portions where the mixture passages are clogged by means of sealing tongues 60, because experience has shown that otherwise too much heat is forwarded to the central portion of the soleplate 11.

A gaseous combustion mixture feeding pipe 61, having a flattened portion 62 (FIG. 3) including a first open end 63, is housed in housing 52, between the flame plate 57 and the roof 53. The portion of the flame plate 57 passing through the housing 52, is welded thereto, thereby establishing a good sealing and ends in a hornlike second opening 64 and passes through the heat-insulating cross partition 20, to which it is likewise welded, thereby supporting said cross partition 20. The cross partition 20 actually consists of a metal plate 65 having a pair of perpendicularly projecting tongue members 66 which are adapted to rest on the soleplate 11. Each side face of said metal plate 65 is sheathed with an asbestos layer 67, 68 and retained against the metal plate 65 by lug members 69, integral with said metal plate 65, thereby establishing a sufficient heat insulation between the main chamber 21 and the rear chamber 22. Within the rear chamber 22, a substantially U-shaped bracket 70 (FIG. 6) is spotwelded at 71 to a pertinent portion of the backwardly sloped upper zone 24. The base portion 72 of the bracket 70 has a central arc portion 73. An inverted U-shaped bracket 74 of similar configuration as the bracket 70, is connected by screws 75 to the base portion 72 and has likewise an arc portion 76, so that between both arc portions, a nozzle member 77 may be gripped.

Nozzle member 77 is best shown in FIG. 5 and comprises a cylindrical central portion with a knurled periphery 78, which is gripped between the said arc portions 73 and 76. The cylindrical central portion 78 ends in a pair of opposite larger diameter end portions 79, 80. A nozzle 81 is screwed into end portion 79 and defines an ejector axis 85. The other end portion 80 is connected to a rigid conduit member 82, ending in a nipple fitting 83. As may be better appreciated in FIG. 2, the nozzle member 77 has a central blind perforation 84 into which ends said rigid conduit member 82. The nozzle 81 has a flattened head portion, so that by means of a suitable wrench, it can be screwed into the end portion 79. As best shown in FIG. 4, the gas-feeding flexible conduit member 39 is fitted over the nipple fitting 83 and is gripped by means of a gripping collar 86.

The inverted U-shaped bracket 74 supports at its free end portions, by means of screws 87, an access plate 88 defining an opening 89 (see FIG. 2) through which air enters the rear chamber 22. If the nozzle 81 has to be replaced, a wrench may be inserted through said opening 89, to carry out the operation. If the nozzle becomes clogged, it may be cleaned by inserting through opening 89, a tool 90 (FIG. 6) having a needle 91 which is to be inserted into the ejector conduit of nozzle 81.

The nozzle member 77 is so arranged within the rear chamber 22, that its ejector axis 85 enters the hornlike second opening 64 of the gaseous combustion mixture feeding pipe 61.

The flexible conduit member 39 is further connected to valve means 92 (FIGS. 1 and 9) for controlling the flow of gas from a gas supply source 93 which is customarily a gas tank, having a check valve 94 with a discharge spout 95.

The valve means 92 include a spout member 96 (FIG. 9) having a screw-threaded bushing 97 slidably mounted thereon. Said bushing 97 is integral with a nut end portion 98 to which a hanger 99 is pivoted, which enables to easily fit the bushing 97 into the discharge spout 95. The spout member 96 is fitted into a needle flow control valve 100 having a needle stem 101 operable by a knob 102 and including a fitting 103. Knob 102 enables controlling the gas flow through passageway 104, as is well known by those skilled in the art. 5

Passageway 104 ends in a diaphragm valve 105 having a diaphragm 106 dividing the valve 105 into a flow control chamber 107 and an upper chamber 108. Flow control chamber 107 is furthermore connected through conduit 117 to said gas-feeding flexible conduit member 39 by means of a fitting clamp 109. Diaphragm 106 is provided with a washer member 110 riveted to an actuating ring member 111. Washer member 110 is housed in upper chamber 108, while ring member 111 is housed in the flow control chamber 107 and sealingly passes through diaphragm 106. Ring member 111 is operatively connected to an L-shaped valve actuating member 112. The end portion 113 of the shorter arm of said L-shaped member 112 bears in a recess 118 of the lower portion of the casing of the diaphragm valve 105. A valve stem 114 is pivoted to said shorter arm of said L-shaped valve-actuating member 112 and has a fluted plunger 115 adapted to block the passageway 104. The longer arm of L-shaped member 112 passes through ring member 111 and position controls plunger 115. A spring 116 urges the diaphragm 106 downwardly and 15 thereby maintains the plunger 115 withdrawn from passageway 104. If the gas pressure within the flow control chamber 107 increases beyond a predetermined value, the pressure generated by spring 116 is overcome and plunger 115 enters into sealing contact with passageway 104, as will be understood by those skilled in the art.

In order to start operation of the flatiron, the knob 102 is turned in anticlockwise direction to allow gas to pass through the valve means 92 into the nozzle 81, which ejects it into the hornlike second opening 64 and drags along a predetermined amount of air, thereby forming in the feeding pipe 61 a gaseous combustion mixture, which enters the housing 52 to pass through the gaseous combustion mixture passages 59. At this instance, it is sufficient to hold a flame, such as a lighted match, adjacent any of the cutout portions 23 to ignite the system.

The amount of gas and air which will enter the bell-shaped housing 52 is so balanced and the distance existing between the indentations 55 and the flame plate 57 is so calibrated, that during continuous operation, a temperature of not more than about 350° C. is generated on the soleplate, which is an optimum temperature for ironing. Tests have shown that an optimum gas pressure is 0.75 kg./cm.². In order to stop the operation, it is merely necessary to turn knob 102 in clockwise direction, so that the needle stem 101 blocks the passageway 104.

Finally it has to be pointed out that conveniently in the front portion of the soleplate 11 adjacent to the tip and on both sides thereof and slightly above the smoothing plane 12, a pair of elongated recesses 119 (only one being visible in FIG. 1) is provided which facilitates ironing shirts and the like garments around a knob whereby part of the knob may enter said recesses 119.

It will be understood that improvements may be introduced in the embodiment described by way of example, and modifications may be made without departing from the scope of the invention, specifically defined in the following claims.

I claim:

1. A gas-heated flatiron, comprising a soleplate defining a smoothing plane and having a front end portion and a rear end portion, a cover shell mounted on said soleplate and projecting beyond said rear end portion and being located above said smoothing plane, an operating handle mounted on said cover shell, a heat-insulating cross partition, said cover shell defining with said soleplate and said partition a main chamber includ-

ing said front end portion and a rear chamber projecting beyond said rear end portion of said soleplate, said rear chamber being heat insulatedly separated from said main chamber by said heat-insulating cross partition, a bell-shaped housing supported by said cover shell within said main chamber and having a heat-radiating infrared ray emitting flame plate mounted in said housing, said flame plate having a plurality of gaseous combustion mixture passages directed towards said soleplate and being spaced apart therefrom, a gaseous combustion mixture feeding pipe having a first open end and a second open end, said first open end being housed in said housing above said flame plate, said second open end being housed in said rear chamber, said feeding pipe sealingly passing through said partition and said housing, a nozzle defining an ejector axis and being housed in said rear chamber and having its ejector axis directed into said second open end, said nozzle being accessible from outside, and a gas-feeding flexible conduit member connected to said nozzle and supported by said operating handle, said gas-feeding conduit member being connectable to a gas supply source and having valve means for controlling the flow of gas towards said nozzle.

2. The gas-heated flatiron as defined in claim 1, wherein the said cover shell includes a backwardly sloped upper zone, a platform mounted on said upper zone and spaced apart therefrom, said platform having a pair of spaced-apart upwardly projecting ears, an outer channelled portion in said platform, spacer projections in said outer channelled portion, said operating handle consisting of two operating handle halves, one of said handle halves being connected to said upwardly projecting ears, while the other handle half is connected to said one handle half, said handle halves are mounted on said spacer projections.

3. The gas heated flatiron as defined in claim 1, wherein said heat-insulating cross partition includes a metal plate supported by said gaseous combustion mixture feeding pipe, said metal plate having a pair of perpendicularly projecting tongue members adapted to rest on said soleplate and a pair of asbestos layers, one attached to each side of said metal plate.

4. The gas heated flatiron as defined in claim 3, wherein said metal plate has lug members bent over said asbestos layers to retain said asbestos layers adjacent said metal plate.

5. The gas-heated flatiron as defined in claim 1, wherein said bell-shaped housing has a roof, spotwelded to said cover shell, said gaseous combustion mixture feeding pipe sealingly entering said bell-shaped housing and said first open end being arranged between said roof and said flame plate.

6. The gas heated flatiron as defined in claim 5, wherein the

portion of said gaseous combustion mixture feeding pipe housed in said housing is flat.

7. The gas-heated flatiron as defined in claim 1, wherein said bell-shaped housing has a free edge provided with bendable lugs, said flame plate being surrounded by a heat-resistant sealing strip in sealing contact with said housing, said bendable lugs being bent over said flame plate and retaining it in said housing.

8. The gas-heated flatiron as defined in claim 7, wherein 10 said gaseous combustion mixture passages of said flame plate in the central portion thereof are clogged by means of sealing tongues.

9. The gas-heated flatiron as defined in claim 1, wherein 15 said second open end of said gaseous combustion mixture feeding pipe is a hornlike opening.

10. The gas-heated flatiron as defined in claim 1, wherein 20 said nozzle is screwed into a nozzle member supported by bracket means, in turn supported by said cover shell, said bracket means further supporting an access plate partially closing said rear chamber and allowing access from outside to said nozzle.

11. The gas-heated flatiron as defined in claim 10, wherein 25 said nozzle member has a rigid conduit member connected to said nozzle and to said gas-feeding flexible conduit member, a cord lift bushing supported by said handle, said gas-feeding flexible conduit member passing through said cord lift bushing.

12. The gas-heated flatiron as defined in claim 1, wherein 30 said cover shell has cutout portions within the zone corresponding to said main chamber, said cutout portion being adjacent to said soleplate.

13. The gas-heated flatiron as defined in claim 1, wherein 35 said valve means include a spout member, a screw-threaded bushing slidably mounted on said spout member and including an integral nut end portion, a hanger pivotally connected to said nut end portion, said spout member being adapted to be connected through said bushing to said gas supply source, said spout member being further connected to a needle flow control valve, said needle flow control valve being further connected to a diaphragm valve, and said diaphragm valve being further connected to said gas-feeding flexible conduit member.

14. The gas-heated flatiron as defined in claim 1, wherein 40 said soleplate defines in its front portion a tip, a pair of elongated recesses arranged adjacent said tip one on each side of said tip to facilitate ironing garments having knobs and the like in the portion around said nob.
